[57] CLAIM

The ornamental design for a safety handle for pipe tong, as shown and described.

DESCRIPTION

FIG. 1 is a perspective view of this design, showing the safety handle mounted on a pipe tong.

FIG. 2 is a perspective view of this design.

FIG. 3 is a front view of this design.

FIG. 4 is a right side view of this design, the left side view being a mirror image thereof.

FIG. 5 is a rear view of this design; and,

FIG. 6 is a top view of this design, the bottom view being a mirror image thereof.

The broken line showing of a pipe tong in FIG. 1 is for illustrative purposes only and forms no part of the claimed design.
